UNITED STATES PATENT OFFICE

2,405,691

ELEVATOR

Charles E. Ellis, Mahwah, N. J., assignor to Sedgwick Machine Works, Inc., Poughkeepsie, N. Y., a corporation of New York

Application August 29, 1944, Serial No. 551,665

7 Claims. (Cl. 187—17)

1

This invention relates to elevators generally, that is, in the sense of including hoists of various kinds. The invention is particularly applicable to heavy duty hoisting or lifting mechanism of the counterbalanced type.

Among the objects of the invention are to so reorganize elevator mechanism as to eliminate the need for, or reduce the mass of, separate conventional counterweights, while retaining the benefits of counterbalanced operation, and to accomplish this in a practical way.

Related objects of the invention are to utilize an essential part of the elevator system, the power plant, as an effective counterbalance, and by so doing, reduce the total weight of the elevator equipment, reduce the cost, and reduce the space required in certain respects.

Other desirable objects attained by the invention will become apparent from the following specification and the accompanying drawings.

Fig. 1 of the drawings is a largely diagrammatic plan view showing at an upper landing a platform elevator embodying the invention. Parts are broken away and in section, to show portions at lower levels.

Fig. 2 is a largely diagrammatic vertical section, taken in general on the line 2—2 of Fig. 1.

Fig. 3 is a largely diagrammatic vertical section taken in general on the line 3—3 of Fig. 1.

Fig. 4 is a fragmentary vertical section, largely diagrammatic, taken in general on the line 4—4 of Fig. 1.

Fig. 5 is a partly diagrammatic fragmentary elevation of one end portion of the counterbalancing carriage, on a larger scale.

Fig. 6 is a partly diagrammatic fragmentary vertical section taken in general on the line 6—6 of Fig. 5.

Fig. 7 is a perspective schematic diagram illustrating operating arrangements and principles of the mechanism.

The elevator shown is of the platform type such as for handling motor vehicles, aircraft and the like, embodying a car 10, operating on suitable guides, in a hatchway 11, between upper and lower landings, such as a flight deck 12, and a hangar or storage deck 13.

The car is operated and counterbalanced by connecting it with a counterweight which is driven by a reversible electric motor constituting an actual part of the counterweight. This will be understood best from Fig. 7, to which reference will now be had.

The platform 10 is suspended by cables or link chains 14, 15, 16, 17, connected at 52, 51, 53 and

2

54, respectively, with the car 10, and connected at 56, 56 with opposite ends of a counterweight beam 18.

On the way from car 10 to counterweight beam 18, link chain 14 passes over sprocket 48 and then over sprocket 43, while link chain 15 passes over sprocket 47 and then over sprocket 44. Similarly, link chain 17 passes over sprocket 49 and then over sprocket 45, while link chain 16 passes over sprocket 50 and then over sprocket 46.

The beam carries an electric motor 19, constituting part of the counterweight load and connected to effect positive drive of the counterweight. Motor 19, through reduction gearing at 15 20, drives sprocket 21 and endless link chain 23, the chain passing over an idler sprocket 22 which is rotatably mounted on the casing of gearing 20. Mounted on stationary axes are upper and lower sprockets 24 and 25 over which chain 23 passes. 20 Sprocket 25 is driven by chain 23, and in turn drives shaft 26 which is mounted in stationary journals.

From sprockets 27 on shaft 26, motion is imparted by an endless link chain 30 to a sprocket 25 which is mounted on a stationary axis. Coaxial with and driven by sprocket 32 is lower sprocket 34 of vertical endless link chain 36 which passes over upper sprocket 38 that is mounted on a stationary axis. Similarly, from sprocket 30 28 on shaft 26 motion is imparted by an endless link chain 29 to a sprocket 31 which is mounted on a stationary axis. Coaxial with and driven by sprocket 31 is lower sprocket 33 of a vertical endless link chain 35 which passes over upper sprocket 37 that is mounted on a stationary axis.

Vertical chains 35 and 36 are connected (at one point each) to beam 18 by "hitches" 39 and 40, respectively. These "hitches" project from shuttles 41 and 42, respectively, which are movable lengthwise of beam 18 to permit the "hitches" to pass around the upper and lower sprockets of chains 35 and 36. The shuttles are confined by upper and lower tracks or guides on beam 18, so that up and down forces are transmitted from chains 35 and 36, through the "hitches" and shuttles to counterweight beam 18. The "hitches" and similar shuttles are disclosed in more detail in my Patent 2,377,483, issued June 5, 1945.

50 When sprocket 21 is driven counterclockwise, this sprocket climbs down chain 23 and at the same time chain 23 is advanced clockwise over sprockets 22, 24 and 25. The rotation of sprocket 25 is imparted, via chains 29 and 30, to vertical chains 35 and 36 to advance them clockwise and

lower the "hitches" 39 and 40, as required for the downward climb of sprocket 21 on chain 23. Thus, the counterweight beam 18 is depressed and the elevator car 10 raised. Clockwise rotation of sprocket 21 raises the counterweight beam 18 and lowers the car 10.

For the most part, the description and explanation just given in connection with Fig. 7, also applies to Figs. 1 through 6 to which the same reference characters have been applied so far as applicable. The counterweight beam 18 is vertically guided in a shaftway 55 (Figs. 1 and 2). Instead of using a single chain 23 as shown in Fig. 7, it is preferable to use two chains 23 and 23a, one on each side of beam 18. This is shown in Figs. 3 and 4. Driven shaft 70 (Figs. 3 and 4) projects from both sides of reduction gear unit 20, and on one end it carries the drive sprocket 21 (see also Fig. 7) which actuates chain 23. On the other end, shaft 70 carries a duplicate drive sprocket 21a (Fig. 4) which actuates an endless link chain 23a which is companion to chain 23 but on the opposite side of gear unit 20. Drive sprocket 21a does not appear in Fig. 3, being directly behind drive sprocket 21. Idler 22 (see Figs. 7, 3 and 4) for chain 23 is located on one side of gear unit 20. On the other side of the gear unit is a corresponding idler sprocket 22a (Figs. 3, 4 and 1) for chain 23a.

As in Fig. 7, chain 23 drives sprocket 25 (Fig. 1) which is mounted on a stationary axle secured to the shaftway structure near the bottom thereof. Mounted on the same axle and secured to sprocket 25 for rotation thereby, is sprocket 27 (Figs. 1, 3 and 4) which drives chain 30 (Figs. 7, 1 and 3). As explained in connection with Fig. 7, driving motion is imparted from chain 30, through sprockets 32 and 34 (Figs. 7, 1 and 3) to lift chain 36 (Figs. 2, 3 and 7).

Chain 23a drives sprocket 25a (Figs. 1 and 3) which is mounted on a stationary axle similarly to sprocket 25. Sprocket 28 (Fig. 1) is coaxial with sprocket 25a and driven thereby. As in Fig. 7, motion is imparted from sprocket 28 to chain 29 (Figs. 1, 3 and 7), sprocket 31 (Figures 1, 3 and 7) and sprocket 33 to lift chain 35 (Figs. 2, 3 and 7).

From the foregoing it will be seen that Figs. 1 through 6 show an arrangement analogous to that shown in Fig. 7; but the form shown in Figs. 1 through 6 is better adapted for incorporation into a working structure. In both cases, the reversible motor is mounted on the counterweight beam 18, which the motor drives down and up. This beam is so cross connected to the elevator platform 10, that the platform is coordinately raised and lowered.

Referring to Fig. 3, the upper sprocket 37 of lift chain 35 is mounted on a stationary part 80 of the shaft structure, while the lower sprocket 33 is mounted on a stationary part 81 of the shaft structure. A strut 82 may be inserted to resist the forces imposed on parts 80 and 81 by lift chain 35; and the axles for sprockets 33 and 37 may pass through the ends of the strut. A corresponding strut 83 is shown in conjunction with lift chain 36, to resist the forces imposed by chain 36 on stationary parts 80 and 84.

The elevator platform 10 and the counterweight beam 18 are guided in their vertical movement by any suitable guide means known to the elevator art. For example, each end of the counterweight beam may cooperate with the flange 58 (Figs. 5 and 6) of a vertical T-rail. The 76 chains positioned on opposite sides of the car-

end of such beam may be provided with extensions 59, 59 which straddle the flange 58; and antifriction rollers such as 51 may engage the rail in any conventional manner.

5 The means for controlling the elevator and assuring safety of operation are not shown, since these may be of any conventional or suitable design. The motor which powers the counterweight and thus effects operation of the elevator is, however, indicated as equipped with an automatic holding brake 60. Other parts normally associated with an elevator motor may be mounted on the traveling beam. The connections through which the motor is controlled may be extended by flexible cable or the like from the beam to a control station on the car or elsewhere.

In compliance with the patent statutes, I have disclosed the best form in which I have contemplated applying my invention, but it will be realized that the disclosure is illustrative and not limiting.

What is claimed is:

1. In an elevator having a car and a counterweight beam operatively connected to the car, means for power driving the counterweight beam to thereby move the car, said power-driving means comprising: vertical endless link chain means adjacent to the beam between the ends thereof, a pair of vertical link chains one adjacent to each end of the beam, a motor mounted on the beam, drive means operatively connecting the motor to said link chain means, driving connections from said link chain means to the chains of said pair of chains, and driving connections 25 from the chains of said pair of chains to the beam, whereby vertical movement is imparted to the beam in response to operation of the motor.

2. In an elevator having a car and a counterweight beam operatively connected to the car, means for power driving the counterweight beam to thereby move the car, said power-driving means comprising: a first vertical endless link chain positioned adjacent to the beam between the ends thereof, a pair of vertical endless link chains one adjacent to each end of the beam, a motor mounted on the beam, a driving connection from the motor to said first chain, driving connections from said first chain to the chains of said pair of chains, and driving connections 35 from the chains of said pair of chains to the beam, whereby vertical movement is imparted to the beam in response to operation of the motor.

40 3. In an elevator having a car and a counterweight beam operatively connected to the car, means for power driving the counterweight beam to thereby move the car, said power-driving means comprising: a first vertical endless link chain positioned adjacent to the beam between the ends thereof, a pair of vertical endless link chains one adjacent to each end of the beam, a motor mounted on the beam, a driving connection from the motor to said first chain, driving connections from said first chain to the chains of said pair of chains, and driving connections 45 from the chains of said pair of chains to the beam, whereby vertical movement is imparted to the beam in response to operation of the motor.

4. In an elevator having a car and a horizontally disposed counterweight beam operatively connected to the car, means for power driving the counterweight beam to thereby move the car, said power-driving means comprising: a first pair of vertical endless link chains positioned adjacent to the beam between the ends thereof, one chain of said pair being on one side of the beam and the other chain of said pair being on the opposite side of the beam, a second pair of vertical endless link chains one adjacent to each end of the beam and one on each side of the beam, a motor mounted on the beam, driving connections from the motor to the chains of the first pair, driving connections from the chains of the first pair to the respective chains of the second pair, and driving connections from the chains of the second pair to the beam, whereby vertical movement is imparted to the beam in response to operation of the motor.

55 5. In an elevator comprising: a vertically movable carriage, a first pair of vertical endless link chains positioned on opposite sides of the car-

60 and the carriage, a second pair of vertical endless link chains positioned on opposite sides of the carriage, a motor mounted on the carriage, driving connections from the motor to the chains of the first pair, driving connections from the chains of the first pair to the respective chains of the second pair, and driving connections from the chains of the second pair to the carriage, whereby vertical movement is imparted to the carriage in response to operation of the motor.

riage, a second pair of vertical endless link chains positioned adjacent to the carriage in spaced relation, a motor mounted on the carriage, driving connections from the motor to the chains of the first pair, driving connections from the chains of the first pair to the respective chains of the second pair, and driving connections from the chains of the second pair to the carriage, whereby the beam is moved vertically in response to operation of the motor.

5. In an elevator having a car and a counterweight operatively connected to the car, means for power driving the counterweight to thereby move the car, said power-driving means comprising: first and second vertical endless link chain means adjacent to the counterweight, a motor mounted on the counterweight, drive means operatively connecting the motor to the first vertical endless link chain means, drive means operatively connecting the first vertical endless link chain means to the second vertical endless link chain means, and drive means operatively connecting the second vertical endless link chain means to the counterweight, whereby vertical movement is imparted to the counterweight in response to operation of the motor.

6. An elevator comprising: a vertically movable carriage, a first vertical endless link chain positioned adjacent to the carriage, a pair of vertical endless link chains positioned adjacent to the carriage in spaced relation, a motor mounted on the carriage, a driving connection from the motor to said first vertical endless link chain, driving connections from said first vertical

endless link chain to the chains of said pair of vertical endless link chains, and driving connections from the chains of said pair of vertical endless link chains to the carriage, whereby the carriage is moved vertically in response to operation of the motor.

7. In an elevator having a car and a horizontally disposed counterweight beam operatively connected to the car, means for power driving the counterweight beam to thereby move the car, said power-driving means comprising: a first pair of vertical endless link chains positioned adjacent to the beam between the ends thereof, one chain of said pair being on one side of the beam and the other chain of said pair being on the opposite side of the beam, a second pair of vertical endless link chains one adjacent to each end of the beam and one on each side of the beam, a third pair of endless link chains, one chain of the third pair being connected to drive a chain of said second pair of chains in response to the motion of one chain of said first pair of chains, and the other chain of said third pair of chains being connected to drive the other chain of said second pair of chains in response to the motion of the other chain of said first pair of chains, a motor mounted on the beam, driving connections from the motor to the chains of said first pair of chains, and driving connections from the chains of said second pair of chains to the beam, whereby vertical movement is imparted to the beam in response to operation of the motor.

CHARLES E. ELLIS.
